LIFTING DEVICE

Johann Friedrich Heinrich Lange, Hamburg,
Germany, assignor to Kampnagel Aktien-
gesellschaft (vormals Nagel & Kaemp), Ham-
burg, Germany

Application July 19, 1934, Serial No. 736,090
In Germany July 22, 1933

8 Claims. (Cl. 254—172)

My invention relates to improvements in lifting devices or cranes intended for lifting floating loads, such as hydro-aeroplane, from, or launching such loads in, a rough sea which imparts 5 to the load an irregular reciprocatory motion relative to the lifting device.

It is an object of my invention to provide means eliminating sudden jerks which are liable to be exerted by the agitated load on the crane when 10 the lifting rope is suddenly tautened and to injure the load and the lifting device.

Another object is to provide means which will lift the floating load smoothly from the crests of the waves with a gradually accelerated speed; to 15 provide means which will facilitate the job of securing the hook to the floating load, for instance the hydro-aeroplane, and to provide a semi-automatic controlling equipment which facilitates the operation.

20 I attain these objects by the provision of two different driving systems which act conjointly on the hook of the winch, the main driving system including a lifting motor serving to lift or to lower the load from or on the sea, whereas an auxiliary 25 driving system including a comparatively small rope-tautening motor serves the sole purpose of lifting and lowering the hook during the up and down movement of the floating load in synchronism with this movement. Preferably, both driving 30 systems operate on a single winding drum independently and simultaneously.

The auxiliary driving system may be preferably provided with a ratchet or similar means preventing a retrograde turn and this ratchet is 35 adapted to be put in operation or to be disabled under electromagnetic control from a switch or other manually operable member installed in the operator's cabin, interlocks being provided preventing the ratchet means from being disabled 40 or enabled unless the auxiliary driving system operates in lifting direction.

If the main motor should operate in the lowering direction at the instant when the operator shifts the switch, this shifting will be effective 45 only to prepare the release or engagement of the ratchet and the actual release or engagement will not take place until the auxiliary driving system is reversed to operate in the lifting direction.

50 The power of the auxiliary driving system is just sufficient to rapidly pull the lifting rope taut, after the hook has been secured to the hydro-aeroplane, and to keep the rope taut under a slight tension, but is too small to interfere with 55 the up and down movement of the hydro-aeroplane on the sea, if the ratchet is disabled. After the rope has been pulled taut, the small auxiliary motor remains energized and, when the hydro-aeroplane is lowered by the waves, it will 60 overcome the torque exerted by the motor and will

turn it in lowering direction. During this floating movement of the hydro-aeroplane on the sea the ratchet means remain completely disabled. When the operator wishes to lift the hydro-aeroplane, he slowly starts the main lifting motor and prepares the engagement of the ratchet by operation of the switch above referred to.

As soon as the hydro-aeroplane will be lifted by the waves, thereafter, the ratchet will be automatically engaged and will prevent any subsequent downward movement of the lifting hook. 10 When the lifting motion caused by the waves approaches the point of reversal and has slowed down to a certain extent, it will be overtaken by the lifting motion imparted to the hook by the 15 slowly operating main driving system and at the instant in which both upward motions, that caused by the waves and that caused by the main driving system, have the same speed, the load will be gradually lifted from the waves without any 20 jerk. A similar operation takes place when the load is to be lowered on the agitated sea. The hydro-aeroplane attached to the hook is slowly lowered by the main driving system while the auxiliary motor is energized, but is unable owing 25 to its limited power to pull in the rope subject to the heavy weight of the load. During this phase of the operation, the ratchet is still in engaged condition. When the hydro-aeroplane approaches the crests of the waves, the operator 30 slows down the main motor to a small lowering speed and operates the switch so as to prepare the disengagement of the ratchet. However, the ratchet will not be actually disengaged at this 35 time because the actual disengagement is conditional upon motion of the auxiliary motor in the lifting direction. The auxiliary motor will operate in the lifting sense, however, and pull in the rope notwithstanding the simultaneous operation of the main motor, as soon as the hydro-aeroplane 40 touches the waves and is lifted by the crests of the same. At this very instant the ratchet will be automatically released and this will permit the hydro-aeroplane to float freely on the sea, owing 45 to the reduction of the lifting power to the small force exerted by the auxiliary motor after the release of the ratchet.

A preferred embodiment of my invention in which the main driving system and the auxiliary driving system are cooperatively connected with a common winding drum, is illustrated on the accompanying drawing.

Fig. 1 shows a diagrammatic axial section through the winch, the two driving motors being shown in elevation.

Fig. 2 is an elevation of the electromagnetically controlled ratchet, partly in section along line 2—2 of Fig. 1.

Fig. 3 shows the circuit arrangement including an automatic switch responsive to the reversal 60

of the auxiliary motor, the switch being illustrated in an enlarged elevational section taken along line 3—3 of Fig. 1.

The winding drum 10 on which the rope 11 carrying the hook 12 is wound is adapted to be operated by the main motor 13 and/or the auxiliary motor 14 through the intermediary of a differential gear. The casing of the main motor 13 which is mounted on the support of the lifting device, for instance on the structure of the crane diagrammatically indicated at 15, forms a trunnion 16 which is coaxially arranged in relation to the winding drum 10 and rotatably supports a gear case 17 which is bolted to the drum. There is also journaled on the trunnion 16 a box-shaped planet gear carrier 18 which is rigidly attached to a shaft 19. The shaft 19 extends coaxially through the drum 10 and its free end is rotatably supported in a bracket 20 and carries an attached gear 21 meshing with a pinion 22 coupled to the auxiliary electric motor 14. The drum 10 has an end wall 23 and a partition 24 which are both rotatably journaled on shaft 19. The planet gear carrier 18 carries one or more planetary gears 25 which mesh with the pinion 26 of the electric motor 13 and with an internally toothed rim 27 attached to the gear case 17.

28 indicates an electromagnetically operated brake of well-known structure which arrests motor 13 whenever the current is cut off and the motor is at rest but is automatically lifted when the motor 13 is started.

On a drum 50 attached to shaft 19 there is fastened a ring 30 provided with ratchet teeth 35 adapted to be engaged by ratchet pawls 31 which are yieldingly held in engagement by springs 32. Solenoids 33 are provided which may disengage the pawls upon energization. As shown in Fig. 2, their cores are attached to rods 35 which are linked to the ratchet pawls and are surrounded by the springs 32.

Moreover, a split slip ring 36 is resiliently clamped on shaft 29 of the auxiliary motor by springs 37, as shown in Fig. 3. The split slip ring carries a piece 38 of insulating material in which a pair of contacts connected to wires 39 and 40 is embedded. These contacts cooperate with a pair of contacts embedded in a stationary insulating block 41 and connected to wires 42 and 43. The wires 39 and 40 may be alternatively connected to the one terminal 44 of a source of current by a manually operable switch indicated at 45, whereas the other terminal 46 is connected to the wires 42 and 43 through the intermediary of coils 47 and 48. It will be realized that either coil 47 or coil 48 will be energized depending upon the position of switch 45 provided, that shaft 29 turns in clockwise direction and, therefore, presses the contacts embedded in the insulating blocks upon each other through the intermediary of the slip ring 36. The coils 47, 48 act oppositely on a relay switch 49 included in the circuit 53 of the solenoids 33.

65 For a clear understanding of the operation let us first consider the conditions prevailing when shaft 29 turns in clockwise direction with reference to Fig. 3 and when the manual switch 45 assumes the position shown in Fig. 3. In this event the contacts will be closed and the coil 47 will be energized pulling the relay switch 49 into the position shown in full lines, thereby de-energizing the solenoids 33. The springs 32 will keep the ratchet pawls 31 in engaged condition. Shaft 29 turning 70 in clockwise direction with reference to Fig. 3

will turn the planet gear carrier 18 so as to cause the winding drum 10 to pull in the rope. Such turning will not be interfered with by the ratchet pawls 31 because a clockwise turn of shaft 29 will cause shaft 19 to turn anti-clockwise with reference to Fig. 2. If now switch 45 is shifted from the position shown in Fig. 3 to its left position, this will immediately energize coil 48 and thereby close switch 49. The consequent energization of solenoids 33 will disengage the ratchet 10 pawls.

As long as the load of the hydro-aeroplane acts on the winding drum 10, it will exert a torque on shaft 19 and shaft 29 so as to separate the slip ring contacts, thereby preventing any control of the ratchet by the manual switch 45.

Owing to the differential action of the epicyclic gear, the main motor 13 cannot operate the winding drum to lift the load unless the ratchet is engaged because with a disengaged ratchet an operation of the main motor 13 will simply cause an idle turn of shaft 19 and of the auxiliary motor 14, while the winding drum 10 is arrested by the load.

Therefore, the lifting operation of winding drum 10 by the main motor 13 is conditional upon the engagement of the ratchet 30, 31 or, in other words, upon a preceding energization of coil 47 or, still in other words, upon the position of switch 45 in the position shown in Fig. 3. It will also appear from the foregoing consideration that the slip ring contacts will remain separated and will prevent a release of the ratchet so long as the winding drum 10 is subjected to the load. Not until the lifting rope will be slackened and will permit the auxiliary motor to operate in the lifting sense, will the slip ring contacts be closed and will release the ratchet if switch 45 has been shifted to the required position. Subsequent to this release the winding drum 10 cannot be subjected to the full load but will be subjected to the small torque only exerted by the auxiliary motor 14 which is just sufficient to keep the lifting rope taut. While the control switch 45 of the ratchet may be shifted by the operator at any time, this will have no immediate effect during the period in which the hook 12 carries the load, or is pulled downwardly by the load, but will only prepare the engagement or disengagement of the ratchet and the actual controlling operation will not take place until the auxiliary motor operates in the lifting sense upon relief of hook 12 from the load and closes the slip ring contacts.

While I prefer the use of an electric auxiliary motor 14, any other suitable source of power may be employed, for instance a weight attached to a rope which is wound on a special drum coupled to pinion 22. If desired, I may arrange motor 14 inside of drum 10, the armature being directly carried by shaft 19 and the pole pieces and pole windings by the drum 10.

The differential effect on the hook 12 may be attained by means other than a planetary gear, for instance by two separate drums, one being driven by the main motor and the other by the auxiliary motor, these drums carrying the ends of a single rope which is reeved over a pulley attached to the hook.

In order to facilitate the difficult job of attaching or detaching the heavy hook 12 to or from the floating hydro-aeroplane while the latter moves up and down, I prefer the provision of special means causing the hook 12 to be lifted and lowered in synchronism with the hydro-aeroplane, before the actual attachment or after the detach-

ment of the hook takes place. For this purpose I have shown the special drum 50 in Fig. 1 which is attached to shaft 19 and carries an auxiliary rope 51 which passes through a guide piece 52 attached to hook 12. This auxiliary rope 51 which may be of light material, so that it can be easily handled, is first attached to the hydro-aeroplane in any suitable manner. This has the effect of turning shaft 19 in synchronism with the movements of the hydro-aeroplane relative to the crane 15. The motion of shaft 19 is transmitted to the winding drum 10, to the rope 11 and to the hook 12, and the latter will be moved up and down in the same manner as the hydro-aeroplane so as to be kept spaced from the same at a certain distance which may be adjusted, as desired, by operation of motor 13. In other words, the distance of the hook 12 from the hydro-aeroplane will not be affected by the waves but can be solely controlled by motor 13. Thus, any collision between the heavy hook 12 and the hydro-aeroplane will be avoided and the hook may be secured to the hydro-aeroplane at leisure. After the hook has been attached to the hydro-aeroplane, the auxiliary rope 51 may be disconnected again.

Similarly, the rope 51 is fastened to the hydro-aeroplane after the same has been launched in the sea, as described, preparatory to the detachment of the hook, thus preventing a collision of the plane with the detached hook.

It is obvious that my invention is capable of numerous modifications without departing from the invention as set forth in the following claims.

What I claim is:

1. Device for lifting and launching objects from and in the sea comprising the combination with a common winding drum and a lifting rope adapted to be attached to the load, of two driving systems of different power, one system being adapted to pull and keep said rope taut and the other system being adapted to lift or lower said load, and of means for preventing a load-lowering motion of said first-mentioned system.
2. Device for lifting and launching objects from and in the sea comprising a hook adapted to be attached to the load, two driving systems of different power differentially connected with said hook, a ratchet device coordinated to the less powerful driving system, means to disable or enable said ratchet device, and a mechanism responsive to a reversal of movement of the last mentioned driving system and adapted to control said means.
3. Device for lifting and launching objects from and in the sea comprising a winding drum, a lifting rope adapted to be wound on said drum and to be attached to said object, two electric motors of different power differentially and drivingly connected to said drum, the less powerful motor being adapted to pull and keep said rope taut and the other motor being adapted to lift or lower said load, a ratchet device coordinated to the less powerful motor, electromagnetic means to disable or enable said ratchet, a slip ring switch coordinated to said less powerful motor and responsive to a reversal of movement of the same and adapted to control said electromagnetic means and a manual switch controlling said electromagnetic means conjointly with said slip ring switch.
4. Device for lifting and launching objects from

and in the sea comprising the combination with a lifting rope adapted to be attached to the load of two driving motors of different power, one motor being dimensioned and designed to exert a continuous pull on said rope which is too small to lift said load but sufficient to keep said rope taut, and the other motor being adapted to lift or lower said load, and of means differentially connecting said motors with said rope so as to enable them to act thereon simultaneously but independently.

5. Mechanism for lifting floating loads, such as seaplanes, from a rough sea comprising a winch, a lifting rope, a main driving mechanism adapted to operate said winch for lifting or lowering the load, an auxiliary driving mechanism adapted to operate said winch for pulling and keeping the lifting rope taut, means adapted to prevent a retrograde operation of said auxiliary driving mechanism, shiftable means adapted to render said first mentioned means effective or ineffective, and means adapted to prevent the operation of said shiftable means as long as the load operates, or tends to operate, said auxiliary driving mechanism in lowering direction.

6. Mechanism for lifting floating loads, such as seaplanes, from a rough sea comprising a winch, a lifting rope, a main driving mechanism adapted to operate said winch for lifting or lowering the load, an auxiliary driving mechanism adapted to operate said winch for pulling and keeping the lifting rope taut, means adapted to prevent a retrograde operation of said auxiliary driving mechanism, shiftable means adapted to render said first mentioned means effective or ineffective, and means adapted to delay the operation of said shiftable means until the auxiliary mechanism operates in lifting direction.

7. Mechanism for lifting floating loads, such as seaplanes, from a rough sea comprising a winch including a main winding drum, a lifting rope adapted to be wound thereon, a load-carrying hook carried by the lifting rope, an auxiliary driving mechanism for said winch adapted to pull and keep the lifting rope taut, an auxiliary cable drum coupled with said auxiliary driving mechanism, and an auxiliary cable wound on said cable drum and adapted to be attached to the floating load to transmit the motion of the latter to said winch, whereby said load-carrying hook will be caused to move in synchronism with the load to facilitate the attachment and detachment of the latter to and from said hook.

8. Mechanism for lifting floating loads, such as seaplanes, from a rough sea comprising a winch including a main winding drum and a winch motor, a lifting rope adapted to be wound on said drum, a load-carrying hook carried by said rope, an auxiliary motor, a differential gear cooperatively connecting both of said motors to said winding drum, the auxiliary motor being dimensioned and designed to exert a continuous pull on said rope sufficient to keep the same taut, an auxiliary cable drum coupled with said auxiliary motor, and an auxiliary cable wound on said cable drum and adapted to be attached to the floating load to transmit the motion of the latter to said main winding drum, whereby said load-carrying hook will be caused to move in synchronism with the load to facilitate the attachment and detachment of the latter to and from said hook.
